(57) **CLAIM**

The ornamental design for a decoration light, as shown and described.

DESCRIPTION

FIG. 1 is a top, front perspective view of a decoration light showing my new design;

FIG. 2 is a bottom, front perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view, shown in an environment of use.

The broken lines illustrate portions of the decoration light and form no part of the claimed design.

The additional broken lines shown in FIG. 9 are directed to environment and are for illustrative purposes only and form no part thereof.
